UNITED STATES PATENT OFFICE.

JOHN S. KRAMER, OF STEGER, ILLINOIS.

DESIGN FOR A COMBINATION-CABINET.

• 54,634.

Specification for Design.

Patented Mar. 9, 1920.

Application filed June 16, 1919. Serial No. 304,706. Term of patent 7 years.

To all whom it may concern:

Be it known that I, JOHN S. KRAMER, a subject of Austria-Hungary, residing at Steger, in the county of Will and State of Illinois, have invented a new, original, and ornamental Design for Combination-Cabinets, of which the following is a specification, reference being had to the accompanying drawing, in which a perspective view of the design is shown.

I claim:—

The ornamental design for a combination cabinet, as shown.

In testimony whereof I affix my signature.

JOHN S. KRAMER.
